UNITED STATES PATENT OFFICE.

RUDOLPH URTEL, OF NIEDERSCHONEWEIDE, GERMANY, ASSIGNOR TO GENERAL ELECTRIC COMPANY, A CORPORATION OF NEW YORK.

VALVE-OPERATING MECHANISM FOR INTERNAL-COMBUSTION ENGINES.

1,156,508.

Specification of Letters Patent.

Patented Oct. 12, 1915.

Application filed January 7, 1911. Serial No. 601,379.

To all whom it may concern:

Be it known that I, RUDOLPH URTEL, a subject of the King of Prussia, residing at Niederschoneweide, Germany, have invented 5 certain new and useful Improvements in Valve-Operating Mechanism for Internal-Combustion Engines, of which the following is a specification.

This invention relates to internal combustion engines, of the type in which the admission and exhaust of the motive gases are controlled by a sleeve interposed between the piston and the walls of the cylinder, and arranged to reciprocate periodically to open 15 and close certain ports.

The object of the present invention is to improve the mechanism by which said sleeve or tubular slide valve is operated.

In the accompanying drawings, Figure 1 20 is a longitudinal section of the cylinder of an internal combustion engine equipped with a tubular slide valve and with one form of my improved valve-operating mechanism; Figs. 2, 3, 4 and 5 show modifications of said 25 operating mechanism; Fig. 6 is a diagram of the theoretical curve desired in the operation of the valve; Fig. 7 shows the curves of movement produced by two eccentrics running at different speeds; and Fig. 8 shows 30 the curve resulting from a plotting of the variations of the two curves shown in Fig. 7.

As will be seen from Fig. 1, the tubular slide valve 1 is interposed between the piston 2 and the walls of the cylinder 3, and is provided with two slots 4 and 5 near its upper end, one of which is located higher up than the other. These slots are adapted to register at different times with the two slots 6 and 7 in the walls of the cylinder; said cylinder slots being at the same level and one constituting the inlet for the explosive mixture while the other serves as the exhaust for the burned gases. The tubular slide valve extends down below the lower open end of 40 the cylinder and is pivotally attached to the operating mechanism, which in Figs. 1 and 2 comprises a lever 8 pivoted to said valve at a point between its ends, said ends being respectively pivoted to rods 9 and 10 adapted 45 to be actuated by eccentrics 11 and 12. The eccentric 11 is arranged to rotate at the same speed as the main shaft which carries the crank pin 13, while the other eccentric 12 rotates at half that speed.

50 The eccentrics impart to the tubular slide

valve an up and down reciprocating movement by means of which the slots in the valve and the cylinder wall are caused to register in proper order and at the proper times and for the proper duration. For instance, the higher slot 4 controls the admission of the mixture and the lower slot 5 the escape of the exhaust gases. Assuming that in Fig. 1 the engine is at the beginning of a power stroke, both ports 4 and 5 are out of line with the ports 6 and 7. When the next upstroke begins, the tubular slide valve must have moved up till the exhaust slot 5 registers with the exhaust port 7. At the conclusion of this stroke, the valve must move 60 downwardly till the admission slot 4 registers with the admission port 6 to permit the piston to suck in a fresh charge. At the end of said stroke the valve must resume the position in which it appears in the drawing and 65 must remain there during the upward compression stroke and the succeeding downward power stroke of the piston. It need not remain entirely stationary during this time, provided it does not move far enough 70 to uncover either of the ports.

From the diagram, Fig. 6, may be seen the different phases of the movement of the valve. The upper and lower dead centers of the crank are indicated by the numerals 85 14 and 15, respectively. The irregular line 16 indicates the theoretical movement of the valve for correct regulation. In actual practice, a curved line 17 may be assumed as the one to which approximation should be made 90 if possible. But such a curve cannot be attained by means of a single eccentric, because the desired curve is not symmetrical on both sides of a perpendicular line 18 drawn through the point at which the reversal of movement occurs, and yet the curve produced by a single eccentric is 95 symmetrical. It is for this reason that I have devised the system shown and described, in which, two eccentrics are used, 100 one rotating at a fraction of the speed of the other, and both acting upon a lever or other element from which the tubular slide valve derives its movement. The preferred ratio is that of 1 to 2; that is to say, one 105 eccentric rotates at one half the speed of the engine shaft and the other at the same speed thereof. By inspection of Fig. 7 the mode in which these two speeds overlap is clear. Curve 19 is that produced by the faster- 110

running eccentric; that is, it shows the movement the valve would make if actuated by that eccentric only. Curve 20 shows the movement produced by the slower running eccentric. Curve 21 is simply a reversal of curve 20, and curve 22 (Fig. 8) is the resultant of curves 19 and 21, being plotted by taking the perpendicular distances between points in these two curves. These perpendicular distances correspond to the valve movement which is produced by the combination of the movements of the two eccentrics. Fig. 8 also contains two lines 23 and 24 parallel with the line 25 representing the middle point of the valve movement. These lines 23 and 24 indicate how far the valve must depart from its middle position before the opening of the slot 4 or 5 occurs. Between these two lines the valve may make any movement necessary without bringing either of the slots into line with its respective port 6 or 7. Fig. 8 shows that there is some slight oscillation of the valve during the time that the slots remain closed; but this is immaterial. Upon comparing Fig. 8 with Fig. 6, it will be apparent that the movement given to the valve is very close to the movement required for a correct regulation thereof.

The two eccentrics may be mounted in various ways. Fig. 1 shows each eccentric on its own shaft; Fig. 2 shows the faster-running eccentric fixed directly on the engine shaft. Figs. 3, 4 and 5 show arrangements in which one of the eccentric rods is used as a lever and is set in oscillating movement about its eccentric by the other eccentric. The lever may be a single-arm, a double-arm or a bell-crank in order to keep the exhaust open long enough and thus avoid an improper re-opening during the compression stroke, the eccentricities of the eccentrics and the lever-arm conditions may be such that the stroke of the tubular slide valve caused by the slower-running eccentric alone is somewhat greater than that which is produced by the quicker-running eccentric alone. It is of further advantage, in order to obtain the opening of the admission port as early as possible, to have the mutual position of the eccentrics such that the slow-running eccentric, in the movement which shuts off the exhaust, will not have reached the middle point between the two dead centers when the quicker-running eccentric, in the movement of like direction, is exactly ninety degrees from the dead centers. By having suitably short eccentric rods, by limiting the crank drive of the tubular valve gear, by making the length of the rod such that it is oblique to the proper lever-arm in its middle position, by elbow-lever action, and similar means, still further advantages may be secured. Instead of taking the quicker-running move-

ment from a special regulating shaft or from an eccentric seated on the crank shaft, it is possible to take it from a suitable point on the connecting-rod. This partial movement is, it is true, not exactly symmetrical, 70 on account of its being derived in an oblique direction and on account of the limited length of the connecting-rod, but it is nearly symmetrical, and by its character comes under the approximately symmetrical movements which are mentioned above and which are obtainable by means of eccentrics or the like. The partial movement which is made more quickly may be produced by means of a swinging member which is set 75 in energetic swinging movement by an eccentric rotating with half the number of revolutions of the motor and the eccentricity of which is only a little smaller than the radius of the swinging member. In this way the rod which sets the swinging member in movement will twice increase and twice diminish, during each rotation of the eccentric, its distance from the point of rotation of the swinging member. The swinging member may be used either as a lever 80 or as a guide or in other suitable manner. For the purpose of combining the two symmetrical movements, the movement of the valve in the latter instance may be derived 85 from a point which is fast connected with the eccentric rod.

In accordance with the provisions of the patent statutes, I have described the principle of operation of my invention, together with the apparatus which I now consider to represent the best embodiment thereof; but I desire to have it understood that the apparatus shown is only illustrative and that the invention can be carried out by other means. 100

What I claim as new and desire to secure by Letters Patent of the United States, is:—

1. In an internal combustion engine, the combination of a cylinder having admission and exhaust ports through its wall adjacent the head of the cylinder, a piston, a tubular slide valve arranged between the piston and the cylinder wall and controlling said ports, and means for moving said valve comprising a shaft which rotates at engine speed, a half-speed shaft, eccentrics on said shafts, and a lever connected to said valve and operated by said eccentrics. 110

2. In an internal combustion engine, the combination of a cylinder having admission and exhaust ports through its wall, a piston, a tubular slide valve arranged between the piston and the cylinder wall and controlling said ports, and means for moving said valve comprising a shaft which rotates at engine speed, a half-speed shaft, eccentrics on said shafts, and a lever having its two ends connected to said eccentrics and operatively connected at an intermediate point to the valve. 120

3. In an internal combustion engine, the combination of a cylinder having admission and exhaust ports through its wall adjacent the head of the cylinder, said ports lying in substantially the same cross-sectional plane, a piston, a tubular slide valve arranged between the piston and the cylinder wall controlling said ports, and means for moving said valve comprising two eccentrics, one rotating at twice the speed of the other,

and means connecting said eccentrics with the valve, said means comprising a lever attached at one point to the valve and at two other points to the eccentrics.

In witness whereof, I have hereunto set my hand this 22nd day of December, 1910.

RUDOLPH URTEL.
